LOCK MECHANISM

John Holt Booth and Jennie Irene Booth,
Lapley, EnglandApplication May 29, 1942, Serial No. 444,984
In Great Britain July 7, 1941

18 Claims. (Cl. 292—165)

This invention relates to lock mechanisms and refers more particularly to slam lock mechanisms primarily intended for the doors of vehicles and the like.

According to the present invention we provide a lock having a casing containing a movable lock bar, a light actuating spring urging said lock bar into the normal projected position, a loading spring opposing movement of the lock bar towards the retracted position, operating means for moving the lock bar into the retracted position, said operating means acting first to render the loading spring wholly or partially ineffective for opposing movement of the lock bar towards the retracted position, and then to move the lock bar into the retracted position against the pressure of the light actuating spring.

The loading spring may act upon a loading lever capable of pivoting and sliding motion, and one arm of this lever may be arranged substantially in line with the lock bar and may be adapted to engage the end thereof.

Alternatively the loading spring may be connected to a pivoted arm acting upon a loading lever capable of pivoting and sliding motion and having a portion normally disposed closely behind the end of the lock bolt.

In such an arrangement the loading lever may be adapted to slide in a direction transverse to the direction of movement of the lock bolt and may engage a guide which limits its movement under the influence of the loading spring in the direction towards the lock bolt.

In such an arrangement the loading lever may be provided with a recess which can be moved by the lock operating means into a position behind the lock bolt.

The light actuating spring may act upon a primary actuating lever engaging the lock bolt and also engaging the loading lever so that when the latter is displaced to render the loading spring wholly or partially ineffective for opposing movement of the lock bar towards the retracted position, the primary actuating lever is operated thereby to withdraw the lock bar.

A secondary actuating lever within the casing may be provided adapted to be moved by the operating means of the lock and adapted to engage and operate the primary actuating lever when the operating means are moved in the lock releasing direction.

The operating means for the lock may comprise a primary operating member and a secondary operating member, these two members being operable from opposite sides of the door to which the lock is applied, the primary operating member operating the primary actuating lever through the medium of the loading lever.

The secondary operating lever within the lock

casing may be adapted to be operated by the secondary operating member.

The secondary actuating lever within the lock casing may be provided with a lateral shoulder adapted to move the loading lever into the inoperative position, i. e. the position in which the loading spring is partially or wholly ineffective, before the secondary actuating lever acts upon the primary actuating lever to withdraw the lock bolt.

The primary operating member may be formed as a push pin having its end engaging the loading lever, and it may be adapted to be adjusted angularly about its own axis, such angular movement being used for locking the secondary actuating lever.

In such an arrangement the push pin forming the primary operating member may have one end formed with a lateral projection or with a recess, which projection or recess is used to lock or release the secondary actuating lever when the primary operating member is turned on its own axis into the appropriate position. The arrangement may be such that when the primary operating member is in the position in which it locks the secondary actuating lever, it can still operate to withdraw the lock bolt and when released will remain in the said position.

Referring to the drawings:

Figure 1 is a sectional view in side elevation showing one construction.

Figure 2 is a sectional view on line 2—2 of Figure 1.

Figure 3 is a sectional view on line 3—3 of Figure 1.

Figure 4 is a view partly in section taken through the primary operating member.

Figure 5 is a section on line 5—5 of Figure 4.

Figure 6 is a fragmentary view in sectional side elevation showing a modified construction.

Figure 7 is a sectional view in side elevation showing a further construction.

In the construction shown, the lock casing 10 is of rectangular form and is made of sheet metal pressings 11, 12, 13. In opposite ends of the lock casing 10 and in alignment, openings 14, 15 are provided, one, 14, for the nose 16 of the lock bar 17, and the other 15, for the long arm 18 of the loading lever 19 which projects from the end of the casing.

Further, this end of the lock casing 10 is provided with a small lug 20 at the lower corner which may be formed as a plate secured within the lock casing by a rivet 74, and having an arm 21 which projects through a slot in the end of the casing 10.

The lock bar 17 is mounted for sliding movement within the lock casing and is provided with the usual nose 16 adapted to give a slam action.

The lock bar is guided by a pair of plates 22 se-

cured within the casing and engaging opposite edges of the lock bar. Further, the lock bar is slotted at 23, and in the slot operates one end 24 of the primary actuating lever 25 pivoted to the casing at 26.

The loading lever 19 comprises one arm 18 which is arranged in alignment with the lock bar 17, and one end of this lever engages the end of the lock bar. At its other end the loading lever is slotted longitudinally at 27 and through the slot passes a pin 28 secured to the door 29 and to a bracket 70 carried on the inner side of the door in which the lock is mounted. Projecting transversely to the main arm 18 of the loading lever is its secondary arm 30 which is very short in relation to the length of the main arm, and connecting this short arm with the arm 21 projecting from the end of the lock casing 10 is the loading spring 31 which is a strong tension spring and tends to slide the loading lever 19 in an end-wise direction towards the lock bar.

The opening 45 in the end of the lock casing through which the loading lever passes is sufficiently wide to allow the loading lever to be displaced downwardly out of line with the lock bar.

The primary actuating lever 25 is mounted upon a pin 26 extending transversely through the lock casing, and it is in the form of a bell-crank lever, one arm of which has its end engaging in the slot 23 of the lock bar and the other arm of which is provided with a laterally projecting lug 32 engaging the underside of the loading lever 19 and with a second lug 33 which is adapted to be engaged by the secondary actuating lever 34.

The secondary actuating lever 34 is of U shape and has the end of one of its limbs pivoted on the pin 26 which accommodates the primary actuating lever, the edge of this limb being engaged by the lug 33 on the primary actuating lever 25, the arrangement being such that if the secondary actuating lever is turned in one direction, the motion is transmitted to the primary actuating lever but reverse movement of the secondary actuating lever is not transmitted to the primary actuating lever.

On one side the secondary actuating lever may be provided with a thickening plate 35 of L shape, one end of which, 36, forms a lateral shoulder and is adapted to engage the loading lever 19. If this plate is provided, the secondary actuating lever on being turned in a clockwise direction (Figure 1), pushes aside the loading lever 19 and relieves the lock bar 17 of the pressure of the loading spring 31 and also acts upon the primary actuating lever. If this thickening plate 35 is omitted, however (see Figure 6), the U shaped secondary actuating lever 34 acts only upon the primary actuating lever 25 and withdraws the lock bar against the full pressure of the loading spring 31.

The primary operating member takes the form of a push pin 37 slidably mounted in an escutcheon 38 adapted to be secured to a suitable part 39 of the door 29. This push pin 37 forming the primary operating member of the lock is disposed vertically and operates against the light spring pressure derived in this case from the loading spring. The pin 37 extends down through an opening 44 in the top of the lock casing.

The upper end of the pin 37 is of non-circular section, and a knob 48 is attached to it, this knob being marked if desired or formed with a radially projecting rib 71 (see Figure 3) to indicate the position into which it has been turned.

The escutcheon 38 carries upon its exterior a circular spring 42 having a projection 43 on one end which extends through an opening 44 in the escutcheon and engages in one of a plurality of recesses 45, 46, 47 in the boss 48 formed integrally with the knob 48, this arrangement allowing the knob to be turned through an angle of 120° and retained in any of three positions by the spring 42.

The lower end of the push pin is recessed or chamfered at one side 49 and gives clearance for the movement of the secondary actuating lever 34, but if the push pin is turned through an angle to either of its other positions, then its lower end acts as a stop to lock the secondary actuating lever 34 against movement.

After the pin 37 forming the primary operating member has been depressed to withdraw the bolt and is released, it automatically moves upwardly into its first position, but if it has been turned into the position in which it locks the lever 34 before depression, it remains in this position until it is moved through a suitable angle about its own axis.

The external or secondary operating member may take the form of a lever handle 50 or a pivoted ring or any other form adapted to be mounted upon an escutcheon plate 51 upon the exterior of the door, and this secondary operating member has an arm 52 projecting through an opening into the lock casing and adapted to engage the free end of the free limb of the U shaped secondary actuating lever 34.

Preferably the escutcheon plate 51 is provided with a pin tumbler lock indicated at 73 which can be used to lock the lever 50 against movement, and which of course can be operated by a key.

Two of the recesses 45, 46 and 47 in the boss 48 are sufficiently long to allow the push pin 37 to be pushed downwardly to release the lock, but the third recess 47 is shorter and prevents the pin 37 from being pushed downwardly so that the pin cannot be operated until it is given a turn through 120° about its own axis.

This provision enables the door to be locked from the inside and prevents it from being opened accidentally and makes it more difficult for the door to be opened by a child from the inside of a vehicle as two movements are required before the lock is released, i. e. the turning of the pin 37 about its own axis, and the downward movement of the pin subsequent to the turning movement.

As will be seen, the lock consists of parts most of which can be produced as sheet metal pressings, and all of which can be very quickly assembled and secured together. Further, the lock is very compact and occupies less space than is usual for this type of lock. In the construction heretofore described, however, the loading lever projects from one end of the lock casing. A more compact construction still is shown in Figure 7, wherein the loading lever 53 is mounted for movement transversely to the direction of movement of the lock bar.

In the construction shown in Figure 7, the main parts are similar to those described with reference to Figures 1 to 5, but the loading spring 54 is connected at one end to a pin 55 and at the other end to an arm 56 which is pivoted at 57 to a pin mounted in the casing. In this way the loading spring 54 acts upon the loading lever as one end of the arm 56 bears upon a flat surface 58 of the loading lever 53. This end of the loading lever 53 is adapted to slide against a rec-

tilinear guide 59 provided in the lock casing, so that the motion of the loading lever towards the lock bar under the influence of the loading spring 54 is limited by the guide 59.

The loading lever is provided with a slot 60 which engages a pin 61 fixed in the lock casing so that the loading lever can slide downwardly and also pivot about the axis of the pin 61.

At one edge the loading lever is provided with a portion 62 which is adapted to engage behind the end of the lock bar 17, and a little higher up the loading lever is recessed as shown at 63 so that if the loading lever is pushed downwardly, it moves into a position in which it is incapable of transmitting the pressure of the loading spring to the lock bar 17.

The loading lever in this construction is adapted to be operated by the push pin 37 having the knob 40 as already described with reference to Figures 1 to 6. In this case the lower end of the push pin 37 instead of being chamfered or recessed is provided with a lateral projection 64 which is adapted to lock the secondary actuating lever 65 which in this case is mounted on a hollow spindle 66 adapted to be operated by an external lever arm (not shown) forming the secondary operating member on the exterior of the door.

A light spring 67 is provided acting upon the secondary actuating lever 65 which can be turned by the exterior lever forming the secondary operating member against the action of this spring causing one end 72 to press down on the top of the loading lever 53 and move it into the position in which the recess 63 moves to a position opposite to the lock bar 17 so that the loading spring 54 becomes inoperative.

Further, as the loading lever 53 moves downwardly, the lower end of a portion 68 thereof acts upon the arm 69 of the primary actuating lever 25, whereby the lock bar is moved back into the retracted position. This primary actuating lever is similar to the lever 25 shown in Figures 1 to 6, but the arm which engages the loading lever is modified mainly by omitting the lug 33.

In all three constructions the push pin 37 forms a stop for upward movement of the loading lever which in turn forms a stop for anti-clockwise movement of the primary actuating lever.

In the construction shown in Figures 1 to 5 and in Figure 6, the loading spring provides spring pressure tending to move the push pin 37 upwardly, and in the construction shown in Figure 7, spring pressure tending to move the push pin 37 upwardly is provided by the spring of the primary actuating lever operating through the loading lever.

In all three constructions the knob associated with the push pin has three positions spaced around its axis. In one of these positions it is locked against downward movement. In either of the other two positions it can be pushed downwardly to release the lock, while in one of these two positions it operates to prevent the lock from being operated from the outside of the vehicle.

In the construction shown in Figures 1 to 5 and in Figure 7, the lock can be operated from the outside of the vehicle, assuming that the knob 40 has been turned to the appropriate position, against the action of a light spring only, but in the construction shown in Figure 6, operation from the exterior of the vehicle is against the loading spring which preferably provides a much heavier loading.

What we claim then is:

1. A lock having a casing containing a movable lock bar, a loading lever having one arm disposed behind said lock bar, and mounted for pivoting and sliding motion, a loading spring acting on said loading lever and opposing movement thereof, a primary actuating lever pivoted to the casing and having one arm engaging the lock bar and the other engaged by the loading lever, a light actuating spring acting on said primary actuating lever and urging the lock bar into the projected position, and operating means for moving the lock bar into the retracted position, said operating means acting to displace said loading lever from behind said lock bar and to rock said primary actuating lever so as to move the lock bar into the retracted position.
2. A lock having a casing containing a movable lock bar, a loading lever having one arm disposed behind said lock bar, and mounted for pivoting and sliding motion, a loading spring acting on said loading lever and opposing movement thereof, a primary actuating lever pivoted to the casing and having one arm engaging the lock bar and the other engaged by the loading lever, a light actuating spring acting on said primary actuating lever and urging the lock bar into the projected position, a secondary actuating lever mounted on the pivot of the primary actuating lever, a lug on the primary actuating lever engaged by the edge of said secondary actuating lever so that movement of the latter in one direction is transmitted to the primary actuating lever, a primary operating member acting on the loading lever, and a secondary operating member acting on the secondary actuating lever.
3. A lock having a casing containing a movable lock bar, a loading lever having one arm disposed behind said lock bar, and mounted for pivoting and sliding motion, a loading spring acting on said loading lever and opposing movement thereof, a primary actuating lever pivoted to the casing and having one arm engaging the lock bar and the other engaged by the loading lever, a light actuating spring acting on said primary actuating lever and urging the lock bar into the projected position, a secondary actuating lever mounted on the pivot of the primary actuating lever, said secondary actuating lever having a part adapted to act on the loading lever and to move its arm away from the end of the lock bar, a lug on the primary actuating lever engaged by the edge of said secondary actuating lever so that movement of the latter in one direction is transmitted to the primary actuating lever, a primary operating member acting on the loading lever, and a secondary operating member acting on the secondary actuating lever.
4. A lock having a casing containing a movable lock bar, a loading lever having one arm disposed behind said lock bar, and mounted for pivoting and sliding motion, a loading spring acting on said loading lever and opposing movement thereof, a primary actuating lever pivoted to the casing and having one arm engaging the lock bar and the other engaged by the loading lever, a light actuating spring acting on said primary actuating lever and urging the lock bar into the projected position, a secondary actuating lever mounted on the pivot of the primary actuating lever, a lug on the primary actuating lever engaged by the edge of said secondary actuating lever so that movement of the latter in one direction is transmitted to the primary actuating lever.

lever, a primary operating member formed as a rotatable push pin acting on the loading lever, one end of said push pin being recessed at one side, said push pin acting as a stop to lock said secondary actuating lever against movement except when said recessed side is disposed towards said lever, and a secondary operating member acting on the secondary actuating lever.

5. A lock having a casing containing a movable lock bar, a loading lever having one arm disposed behind said lock bar, and mounted for pivoting and sliding motion, a loading spring acting on said loading lever and opposing movement thereof, a primary actuating lever pivoted to the casing and having one arm engaging the lock bar and the other engaged by the loading lever, a light actuating spring acting on said primary actuating lever and urging the lock bar into the projected position, a secondary actuating lever mounted on the pivot of the primary actuating lever, a lug on the primary actuating lever engaged by the edge of said secondary actuating lever so that movement of the latter in one direction is transmitted to the primary actuating lever, a primary operating member formed as a rotatable push pin acting on the loading lever, an escutcheon supporting said push pin, said escutcheon having an opening through its wall, a spring mounted on the exterior of said escutcheon and having a projection which extends through said opening, said push pin being provided with longitudinal grooves spaced around its circumference, which grooves are engaged in turn by said projection as the pin is turned on its own axis, said engagement serving to retain the pin in any one of a plurality of angular positions, one end of said push pin being recessed at one side, said push pin acting as a stop to lock said secondary actuating lever against movement except when said recessed side is disposed towards said lever, and a secondary operating member acting on the secondary actuating lever.

6. A lock having a casing containing a movable lock bar, a loading lever disposed behind said lock bar, said loading lever being mounted for movement in two directions, one in line with the lock bar, and one transversely to the length of the lock bar, a loading spring acting on said loading lever and opposing movement thereof in the direction in line with the lock bar and thus opposing retraction of the lock bar, a primary actuating lever pivoted to the casing and having one arm engaging the lock bar and the other engaged by the loading lever, a light actuating spring acting on said primary actuating lever, a primary operating member for rendering the loading spring ineffective for opposing the retraction of the lock bar, and for moving the lock bar into the retracted position, a secondary operating member for moving the lock bar into the retracted position, means on the primary operating member for locking the secondary operating member, said primary operating member being movable into a plurality of positions, in one of which it locks the secondary operating member, and means for retaining the primary operating member in any of said positions.

7. A lock according to claim 6, wherein the primary operating member is movable into any of three positions, in one of which it is locked against movement for operating the lock bar and also locks the secondary operating member, in another of which it can be moved to withdraw the lock bar but locks the secondary oper-

ating member, and in the third of which it can be moved to withdraw the lock bar and permits the secondary operating member to be operated.

8. A lock according to claim 6, wherein the primary operating member is formed as a push pin mounted for endwise movement and for movement around its own axis, the latter movement permitting it to be moved into any one of three positions, means for retaining the primary operating member in any of said positions, in one of which it is locked against movement for operating the lock bar and also locks the secondary operating member, in another of which it can be moved to withdraw the lock bar but locks the secondary operating member, and in the third of which it can be moved to withdraw the lock bar and permits the secondary operating member to be operated.

9. A lock according to claim 6, wherein the primary operating member is formed as a push pin mounted for endwise movement and for movement around its own axis, the latter movement permitting it to be moved into any one of three positions, the means for retaining the primary operating member in any one of said positions comprising an escutcheon supporting said push pin, said escutcheon having an opening through its wall, a spring mounted on the exterior of said escutcheon and having a projection which extends through said opening, said push pin being provided with longitudinal grooves spaced around its circumference, which grooves are engaged in turn by said projection as the pin is turned on its own axis.

10. A lock having a casing containing a movable lock bar, a loading lever having one arm disposed behind said lock bar, and mounted for pivoting and sliding motion, a loading spring acting on said loading lever and opposing movement thereof, a primary actuating lever pivoted to the casing and having one arm engaging the lock bar and the other engaged by the loading lever, a light actuating spring acting on said primary actuating lever and urging the lock bar into the projected position, a secondary actuating lever mounted on the pivot of the primary actuating lever, a lug on the primary actuating lever engaged by the edge of said secondary actuating lever so that movement of the latter in one direction is transmitted to the primary actuating lever, a primary operating member formed as a rotatable push pin acting on the loading lever, a secondary operating member acting on the secondary actuating lever, means on the primary operating member for locking the secondary operating member, said primary operating member being movable into a plurality of positions, in one of which it locks the secondary operating member, and means for retaining the primary operating member in any of said positions.

11. A lock having a casing containing a movable lock bar, actuating means lightly loaded by an actuating spring, and urging said lock bar into the normal projected position, a loading lever being mounted for movement in two directions, one in line with the lock bar, and one transversely to the length of the lock bar, a loading spring acting on said loading lever and opposing movement thereof in the direction in line with the lock bar and thus opposing retraction of the lock bar, and operating means for moving the lock bar into the retracted position, said operating means acting on the loading lever to move it transversely to the length of the lock

bar, so that the loading spring no longer opposes retraction of the lock bar, said operating means also moving the actuating means so as to retract the lock bar.

12. A lock having a casing containing a movable lock bar, actuating means lightly loaded by an actuating spring, and urging said lock bar into the normal projected position, a loading lever disposed behind said lock bar, said loading lever having a slot engaged by a pin fixed to the casing whereby said loading lever is mounted for movement in two directions, one in line with the lock bar, and one transversely to the length of the lock bar, a loading spring acting on said loading lever and opposing movements thereof in the direction in line with the lock bar and thus opposing retraction of the lock bar, and operating means for moving the lock bar into the retracted position, said operating means acting on the loading lever to move it transversely to the length of the lock bar, so that the loading spring no longer opposes retraction of the lock bar, said operating means also moving the actuating means so as to retract the lock bar.

13. A lock having a casing containing a movable lock bar, a loading lever disposed behind said lock bar, said loading lever being mounted for movement in two directions, one in line with the lock bar, and one transversely to the length of the lock bar, a loading spring acting on said loading lever and opposing movement thereof in the direction in line with the lock bar and thus opposing retraction of the lock bar, a primary actuating lever pivoted to the casing and having one arm engaging the lock bar and the other engaged by the loading lever, a light actuating spring acting on said primary actuating lever, a primary actuating member acting on the loading lever and a secondary operating member operating said primary actuating lever.

14. A lock having a casing containing a movable lock bar, a loading lever disposed behind said lock bar, said loading lever being mounted for movement in two directions, one in line with the lock bar, and one transversely to the length of the lock bar, a loading spring acting on said loading lever and opposing movement thereof in the direction in line with the lock bar and thus opposing retraction of the lock bar, a primary actuating lever pivoted to the casing and having one arm engaging the lock bar and the other engaged by the loading lever, a light actuating spring acting on said primary actuating lever, a secondary actuating lever mounted on the pivot of the primary actuating lever, a primary operating member acting on the loading lever and a secondary operating lever acting on said secondary lever.

15. A lock having a casing containing a movable lock bar, a loading lever disposed behind said lock bar, said loading lever having a long arm disposed behind and substantially in line with the lock bar, said loading lever having a slot engaged by a pin fixed to the casing whereby said loading lever is mounted for movement in two directions, one in line with the lock bar, and one transversely to the length of the lock bar, a loading spring acting on said loading lever and opposing movement thereof in the direction in line with the lock bar and thus opposing retraction of the lock bar, a primary actuating lever pivoted to the casing and having one arm

engaging the lock bar and the other engaged by the loading lever, a light actuating spring acting on said primary actuating lever, a secondary actuating lever mounted on the pivot of the primary actuating lever, a lug on the primary actuating lever engaged by the edge of said secondary actuating lever so that movement of the latter in one direction is transmitted to the primary actuating lever, a primary operating member acting on the loading lever and a secondary operating lever acting on said secondary actuating lever.

16. A lock having a casing containing a movable lock bar, a loading lever mounted for pivoted and sliding movement, said loading lever being disposed transversely to the lock bar and behind same, and having one edge directed towards the end of the lock bar, said edge having a notch, a pivoted arm acting on said loading lever, a loading spring acting on said arm, a stop on the casing engaging the loading lever and limiting its movement towards the lock bar, a primary actuating lever pivoted to the casing and having one arm engaging the lock bar and the other engaged by the loading lever, a light actuating spring acting on said primary actuating lever, and operating means adapted to slide said loading lever endwise so as to bring the notch in the edge thereof opposite to the end of the lock bar, and to rock said primary actuating lever so as to move the lock bar into the retracted position.

17. A lock having a casing containing a movable lock bar, a loading lever mounted for pivoted and sliding movement, said loading lever being disposed transversely to the lock bar and behind same, and having one edge directed towards the end of the lock bar, said edge having a notch, a pivoted arm acting on said loading lever, a loading spring acting on said arm, a stop on the casing engaging the loading lever and limiting its movement towards the lock bar, a primary actuating lever pivoted to the casing and having one arm engaging the lock bar and the other engaged by the loading lever, a light actuating spring acting on said primary actuating lever, a primary operating member acting on the loading lever, a secondary actuating lever, a light spring acting thereon, and a secondary operating member acting on the secondary actuating lever.

18. A lock having a casing containing a movable lock bar, actuating means lightly loaded by an actuating spring and urging said lock bar into the normal projected position, a loading lever disposed behind said lock bar, said loading lever being mounted for movement in two directions, one in line with the lock bar and one transversely to the length of the lock bar, a loading spring acting on said loading lever and opposing movement thereof in the direction in line with the lock bar and thus opposing retraction of the lock bar, and operating means formed as an endwise movable push pin projecting from the edge of the casing, said operating means acting on the loading lever to move it transversely to the length of the lock bar, so that the loading spring no longer opposes retraction of the lock bar, said operating means also moving the actuating means so as to retract the lock bar.
